The diagram illustrates a circuit for a motor control system. The main circuit consists of a motor (M) connected in series with a generator (G). The generator (G) is connected to a complex control section. This control section includes a resistor labeled 39, a resistor labeled 5, and a resistor labeled 38. The circuit also features a resistor labeled 41, a resistor labeled 63, a resistor labeled 60, a resistor labeled 58, and a resistor labeled 57. The resistor labeled 57 is connected to ground. The resistor labeled 58 is connected to the generator (G). The resistor labeled 60 is connected to the generator (G) and the resistor labeled 63. The resistor labeled 63 is connected to the resistor labeled 41. The resistor labeled 41 is connected to the resistor labeled 38. The resistor labeled 38 is connected to the resistor labeled 39. The resistor labeled 39 is connected to the resistor labeled 5. The resistor labeled 5 is connected to the generator (G).

ELECTRICAL SYSTEM.

1,367,155.

Specification of Letters Patent.

Patented Feb. 1, 1921.

Application filed May 16, 1916. Serial No. 97,800.

To all whom it may concern:

Be it known that I, WALTER O. LUM, a citizen of the United States, and a resident of Pittsburgh, in the county of Allegheny and State of Pennsylvania, have invented a new and useful Improvement in Electrical Systems, of which the following is a specification.

My invention relates to electrical systems and particularly to such systems as are employed to control the voltage of electric generators.

My invention has for its object to provide a simple and efficient means for temporarily impressing a relatively high voltage upon the field windings of an electric generator in order to cause the voltage of the generator to more quickly reach a value corresponding to the adjustment of the controlling mechanism.

In the operation of reversing rolling mills and similar machines where frequent stops and reversals are necessary, it is desirable that the voltage of the generators which supply energy to the driving motors shall be quickly responsive to the adjustments of the controlling devices. It is well known that, if only the normal exciter voltage be applied to the field-magnet windings of a generator, an appreciable amount of time must elapse before the generator voltage reaches a value corresponding to the position of the controller. The period of time necessary to overcome the inductance of the generator field circuit may be materially shortened by temporarily applying an abnormally high voltage.

I provide an arrangement comprising the usual resistor in circuit with the generator field-magnet windings and a series of electromagnetic switches for controlling the resistor. A differentially wound relay is provided with two coils, one of which is in circuit with the actuating coils of the electromagnetic switches, and the other of which is connected to the terminals of the generator. A controller, which controls the circuits of the actuating coils of the electromagnetic switches, automatically determines the number of such coils that are in circuit with the relay coil.

The relay operates to shunt the field resistor when the generator voltage is below the normal value corresponding to the position of the controller. By means of this

arrangement, a relatively heavy current traverses the field-magnet windings of the generator until the voltage reaches the normal value corresponding to the adjustment of the controller, whereupon the relay operates automatically to open a shunt for the resistor.

In the accompanying drawings, Figure 1 is a diagrammatic view of the main circuits of two generators and two motors connected in a closed circuit, and an exciter generator for supplying current to a part of the motor field-magnet windings. Fig. 2 is a diagrammatic view of the circuits of the field-magnet windings of the motors and generators, together with the controlling switches therefor. Fig. 3 is a chart or table indicating the sequence of operation of the various switches. Fig. 4 is a diagrammatic view of the circuits for controlling the various switches illustrated in Figs. 1 and 2, together with the relay for automatically controlling the resistance of the generator field circuits.

Two generators G and two motors M are connected in series in a closed circuit, the generators and the motors being disposed alternately in the circuit. The field excitation of the generators and motors is controlled by electromagnetic switches 1 to 35, inclusive. An exciter E, which supplies current to motor field-magnet windings 37, is provided with a field-magnet winding 38 that is in series with the generators G and the motors M.

A resistor 39, that is in series with the motor field-magnet windings 37, is controlled by electromagnetic switches 9, 10 and 11. A resistor 40, that is in series with motor field-magnet windings 41, is controlled by electromagnetic switches 24 and 25 which are caused to operate in the manner of fluttering relays, under conditions to be later described, and by electromagnetic switches 26 to 35, inclusive. The motor field-magnet windings 41 are arranged to be energized by any suitable source of constant voltage. The voltage applied to the motor field-magnet windings 37 is variable, since the voltage of the exciter E varies in accordance with the current traversing the main circuit. In the illustrated embodiment of the invention, 37 and 41 are shown as separately excited windings.

A resistor 43, which is connected in series with the generator field-magnet windings 110

44, is controlled by electromagnetic switches 12 and 13 which are caused to operate in the manner of fluttering relay switches during deceleration, as will be later described, 5 electromagnetic switches 14 to 21, inclusive, and electromagnetic switches 22 and 23 which may be termed generator field-forcing switches. The direction of the current traversing the generator field-magnet windings 10 44 is controlled by electromagnetic reversing switches 1, 2, 3 and 4. The connections of motor field-magnet windings 37 to the terminals of exciter E are similarly controlled by reversing switches 5, 6, 7 and 8.

15 The circuits for controlling the actuating coils of the electromagnetic switches 1 to 35, inclusive, are illustrated in Fig. 4. For convenience, the actuating coils have been designated by the same reference numerals 20 that are applied to the corresponding switches. A controller 45 effects the closing of the several switches in the sequence indicated by the chart shown in Fig. 3.

A relay 47 comprises a pivotally mounted 25 arm 48 for effecting the engagement and disengagement of contact members 49 and 50. The relay 47 is provided with two actuating coils 52 and 53 which tend to actuate the lever 48 in opposite directions. The coil 52 30 is connected across the terminals of one of the generators G and is, therefore, responsive to generator voltage. The coil 53 is connected in series with the actuating coils of switches 14 to 21, inclusive. The actuating coils of the switches 14 to 21 are connected in parallel relation, and the coil 53 is, therefore, energized to a degree corresponding to the number of actuating coils that are connected in circuit by the controller 45. By means of this arrangement, the 40 resistance of the circuit comprising the coil 53 varies in accordance with the position of the controller and the number of electromagnetic switches operating to shunt sections of the resistor 43.

The relation of the coils 52 and 53 and the actuating coils in series with the relay coil 53 are such that the ampere turns of the coils 52 and 53 are equal when the generator 50 voltage reaches a value corresponding to the position of the controller 45. The relay switch 47 is provided, also, with an auxiliary coil 54 that is in series with the contact members 49 and 50. The function of the coil 54, 55 which exerts a comparatively slight pull, is to insure that the contact members 49 and 50 are positively separated upon the opening of the relay. This action prevents continual sparking at the contact members, which would otherwise occur when the coils 52 and 53 are energized to a substantially equal degree.

The relay switch 47 controls the circuits of the actuating coils of switches 22 and 60 23. The latter switches control a shunt cir-

cuit for the major portion of the resistor 43 and thus operate to materially increase the electromotive force applied to the generator field-magnet windings 44 when the relay switch 47 is closed by reason of the 70 unbalanced pulls of the coils 52 and 53.

The switches 12 and 13, which control a section of the resistor 43, are controlled during deceleration by a relay 56 having an actuating coil 57 connected across a reactive 75 shunt 58 in the main circuit. Switches 24 and 25 for controlling a shunt circuit for the major portion of the resistor 40 are controlled by a relay 59 having an actuating coil 60 connected across the shunt 58 in the 80 main circuit. The effect of the operation of the relay 59 is reversed by a reverse-current relay 61 having a shunt actuating coil 62 and a series actuating coil 63 that is also connected across the shunt 58, which relay 85 61 controls also the effect of the operation of the relay 56.

It may be assumed that the controller 45 is in its illustrated or inoperative position and that the generators are being mechanically driven. The voltage of the generators is substantially zero, since the respective field-magnet windings 44 are not energized. The motor field-magnet windings 41 are energized, since they are connected between 95 the terminals of a constant-potential source. The motor field-magnet windings 37 are de-energized because their circuits are open at the reversing switches 5, 6, 7 and 8. It may be assumed further that it is desired 100 to operate the motors in the forward direction.

In the "off" position of the controller 45, the switch 11 is closed to complete a shunt circuit for the major portion of the resistor 105 39 and thus insure a relatively strong field for the motors M upon the operation of the reversing switches 5 and 7 or 6 and 8, as the case may be. The actuating coils of switches 12 and 13 are also energized by a circuit 110 comprising relay 61. The switches 26 and 27 are also closed when the controller is in its "off" position to complete a shunt circuit for substantially the entire resistor 40 in order that the field-magnet windings 41 115 may be traversed by a current of relatively high value when the motors are started.

It may be assumed that the controller 45 is actuated to the right, as viewed in Fig. 4. In position *a* of the controller, the actuating coils of reversing switches 1 and 3 are energized to complete a circuit for the generator field-magnet windings 44 through that portion of the resistor 43 that is not shunted by the switches 12 and 13, and through field-discharge switch 65, which has been previously closed. The reversing switches 5 and 7 are also closed, in the first position of the controller, to connect the motor field-magnet windings 37 and a por- 130

tion of the resistor 39 (not controlled by the switch 11) in circuit with the armature windings of exciter E.

In position *b* of the controller, a circuit 5 is completed for the actuating coil of switch 14 which extends from the positive line conductor of the exciting circuit through contact segment 66, contact segment 67, which is electrically connected to contact 10 segment 66, contact member 68, conductor 69, actuating coil of switch 14, and coil 53 to the negative line conductor.

The switch 14 operates to shunt a section 15 of the resistor 43 and thus increases the field excitation of the generators. The shunting of a section of the resistor 43 by the switch 14 causes the voltage of the generators G to assume a corresponding value, but an appreciable period of time is required for the 20 voltage to reach the value corresponding to the adjustment of the controller after the switch 14 has operated.

The resistance of the circuit comprising 25 the coil 53 which, in the "off" position of the controller, comprises the actuating coil of switch 26, has been decreased upon the connection of actuating coil of switch 14 in parallel relation to the actuating coil of switch 26. A correspondingly strong 30 pull is exerted by the coil 53 to effect the engagement of the contact members 49 and 50. The contact members are closed, therefore, to complete a circuit for the actuating coils of switches 22 and 23, and the 35 latter operate to complete a shunt for a comparatively large portion of the resistor 43 and thus temporarily permit the generator field-magnet windings 44 to be energized by an abnormally heavy current.

40 As soon as the generator voltage reaches a value corresponding to the position of the controller, the coil 52 is energized to exert a pull substantially equal to that of the coil 53, and the relay opens to effect the 45 opening of switches 22 and 23. The generator windings are now supplied with current at normal value, and the generator voltage remains substantially constant. In the same manner, the actuation of the controller 50 to its succeeding positions *c*, *d*, *e*, *f*, *g* and *h* operates to effect the closing of switches 15, 16, 17, 18, 19, 20 and 21 to increase the voltage of the generators and thereby accelerate the motors.

55 It will be understood that the operation of the controller may be step by step or it may be actuated quickly to either of its operating positions, whereupon the several switches operate automatically and in sequence. The progressive operation of the 60 several switches is insured by the provision of suitable interlocks which control the actuating coil of the succeeding switch to close. The circuits of the actuating coils are

thus controlled by the preceding switch to 65 close and the controller.

During the acceleration of the motors by controlling the generator voltage, the relay switch 47 operates in the manner above described whether the controller is actuated 70 step-by-step or is actuated to either of its operative positions by a single movement. The completion of the circuits for the respective actuating coils of the switches 15 to 21, inclusive, further decreases the resistance of the circuit comprising the relay coil 53, and the latter is energized by an 75 increasingly heavy current corresponding to the adjustment of the controller. The relay remains closed, therefore, until the coil 52 80 is energized at correspondingly higher values.

When the controller occupies position *h*, switches 9 and 10 are closed in anticipation of the gradual insertion of the resistor 39 85 in the circuit of the motor field-magnet windings 37. Switches 28 to 35, inclusive, also close in order that the resistor 40 may be inserted gradually in circuit with the motor field-magnet windings 41. The circuit of the actuating coil of switch 28 is closed by the interlock 70 connected to the switch 21. The switches 28 to 35, inclusive, then close in order, the circuits of the actuating coils of the respective switches being 90 completed by the interlock of the preceding switch to close.

In position *i* of the controller, the switch 26 opens to insert a section of the resistor 40 in series with the field-magnet windings 95 41, to further accelerate the motor. The circuits of the actuating coils of switches 27 to 35, inclusive, are respectively controlled by interlocks of the preceding switches. Current may be supplied to the 100 actuating coils of switches 27, 28, 29, 30, 32 and 34 through the controller independently of the interlocks.

The actuation of the controller to position *j* effects the opening of switch 27, and, as 110 the controller is actuated to succeeding positions *j*, *k*, *l*, *m* and *n*, the several switches open in order to gradually insert the resistor 40 and thereby weaken the fields of the motors. The switches 11, 10 and 9 open 115 in the order named when the controller successively occupies the positions *i*, *h* and *m*. The motors now operate at their normal operating speeds, with the generator voltage at a normal value and the fields of the 120 motors weakened to a normal degree.

Owing to the motors M being supplied not only with constant-potential field-magnet windings 41 but also with the field-magnet windings 37, which are energized in accordance with the value of the current traversing the exciter field-magnet winding 38, which latter is in series with the motor ar-

matures, the motors have the characteristics of compound-wound machines. They are, however, superior to compound-wound motors in that it is not necessary to reverse the 5 main armature current and because, by means of the resistor 39, the ratio between the no-load speed and the full-load speed may be varied as desired and may, indeed, be maintained practically constant. The 10 constant value would be obtained by providing as many switches 9, 10, 11 for short-circuiting the resistor 39 as there are switches 26 to 35 and by closing one of the first-named switches simultaneously with the 15 closing of each of the last-named switches. This refinement is not always essential; but an approximation to the desired result is obtained by manipulating the switches 11, 10 and 9 in conjunction with the switches 20 26 to 35, as above described.

If, during the acceleration of the motors, by weakening their magnetic fields, the current traversing the main circuit exceeds a predetermined value, the relay 59 operates 25 to complete circuits for the actuating coils of switches 24 and 25, and the latter operate to temporarily complete a shunt for the variable portion of the resistor 40 and thus strengthen the fields of the motor. The relay 30 59 operates in the manner of a fluttering relay during such time as the current values in the main circuit exceed the predetermined value. In this manner, the current traversing the main circuit is automatically maintained within predetermined limits.

When it is desired to stop the motors, the controller is actuated toward its "off" position. The motors then operate as generators when the electromotive forces generated by 40 them exceed the voltage of the generators. As the controller is actuated gradually to its inoperative position, the motor-accelerating switches are closed in an order substantially inverse to that in which they opened 45 and the motor fields are strengthened to increase the voltage of the motors. The generator switches are opened to weaken the field of the generators, the switches 22 and 23 remaining open, and thus permit a correspondingly heavier current to traverse the 50 main circuit which constitutes a dynamic-breaking circuit for the motors.

The coil 63 of relay 61, which normally opposes shunt coil 62, now assists the latter 55 because the current traverses the main circuit in the opposite direction. The relay 61 is accordingly actuated to its upper position to reverse the effects produced by the operation of the relay 59 and to render the relay 60 56 effective. In case the current traversing the main circuit during the operation of dynamic braking exceeds a predetermined value, the relay 56 operates to establish a circuit for the actuating coils of switches 12 65 and 13, this circuit having been broken by

the relay 61 when the latter assumed its upper position. The switches 12 and 13 temporarily shunt a portion of the resistor 43 to increase the field excitation of the generators. The current traversing the main circuit 70 is accordingly decreased to a corresponding degree. The relay 56 operates as a fluttering relay whenever the current exceeds the predetermined value.

In a similar manner, the relay 59 operates 75 also as a fluttering relay to cause the oscillation of switches 24 and 25 during such times as the current traversing the main circuit exceeds the predetermined value. It will be noted that the relays 56, 59 and 61 80 operate to prevent the current traversing the main circuit from reaching excessive values during the operation of bringing the motors to rest.

The relays 56, 59 and 61 thus effectively 85 control the resistors 40 and 43. During acceleration, the relay 61 is in its illustrated, lower position to maintain the switches 12 and 13 closed, and the relay 59 flutters to close the switches 24 and 25. During de- 90 acceleration, the relay 61 assumes its upper position, and the relays 56 and 59 both flutter, the former to close the switches 12 and 13 and the latter to open the switches 24 and 25.

When it is desired to operate the motors in the opposite direction, the controller is actuated to the left, as viewed in Fig. 4. Reversing switches 2 and 4 close to reverse the direction of the exciting current through 100 generator field-magnet windings 44, and thereby reverse the direction of the electro-motive force applied to the motor-armature windings. The current traversing the field-magnet winding 38 of exciter E is also 105 reversed. The reversing switches 6 and 8 operate, however, to reverse the direction of current through the motor field-magnet windings 37. The motors operate in the reverse direction, since the current through 110 their armature windings is reversed while the direction of current through the motor field-magnet windings remains the same. The operation is otherwise as described above in connection with the acceleration of 115 the motors in the forward direction.

It will be observed that, while the motors are being supplied with current, the switches 12 and 13 are maintained closed, as the relay 61 always occupies its lowest position. In the sequence chart, Fig. 3, these switches are, however, shown as being open in positions *a* to *p* of the controller. This is because the chart applies in other respects to positions which the controller occupies when the motors are being stopped and the switches 12 and 13 are opened and closed by the action of the relay 56, the relay 61 occupying its upper position, as hereinbefore stated.

It will be noted that I provide a system by means of which the voltage of a generator may be increased much more rapidly than is possible when only the normal exciting voltage is applied to the generator field-magnet windings. By means of this arrangement, the loss of much valuable time in the operation of rolling mills and similar machines is avoided.

10 While I have shown and described a system comprising two generators and two motors, which represents an actual installation of a system embodying my invention, it will be understood that this arrangement is illustrative only and that my invention may be applied with equal facility and effectiveness to a system embodying a single generator which is connected to a similar intermittent load.

15 20 I claim as my invention:

1. In an electrical system, the combination with a generator having a field-magnet winding, and a resistor in circuit with said winding, of a plurality of electromagnetic switches for controlling said resistor, a controller for said switches, and a relay for controlling said resistor in accordance with the value of the voltage of said generator relatively to the normal voltage value corresponding to the position of said controller.

2. In an electrical system, the combination with a generator having a field-magnet winding, and a resistor in circuit therewith, of means for controlling said resistor comprising a plurality of progressively actuated electromagnetic switches, a controller for said switches and a relay having two coils, one of which is connected to the terminals of said generator and the other of which is in circuit with the actuating coils of said switches.

3. In an electrical system, the combination with a generator having a field-magnet winding, and a resistor in circuit therewith, of means for controlling said resistor comprising a plurality of progressively actuated electromagnetic switches, a relay having two opposing coils, one of which is connected across the terminals of said generator and the other of which is in circuit with the actuating coils of said switches, and a controller for said switches and for controlling the number of actuating coils in circuit with said second relay coil.

4. In an electrical system, the combination with a generator, of means for controlling the field excitation of said generator comprising a plurality of electromagnetic switches having actuating coils connected in parallel relation, a relay having two coils, one of which is responsive to the voltage of said generator and the other of which is in series with said actuating coils, and means for controlling the circuits of said coils.

5. In an electrical system, the combination with a generator, of means for controlling the field excitation of said generator comprising a resistor, a plurality of electromagnetic switches for controlling said resistor, and means for controlling said resistor in accordance with the relation of the voltage of said generator to the number of actuating coils of said switches that are energized.

6. In an electrical system, the combination with a generator and a motor, of means for controlling the field excitation of said motor and of said generator, said means comprising a plurality of electromagnetic switches, a relay for increasing the field excitation of the generator while the voltage of the latter is less than that corresponding to the operation of certain of the switches, and means for controlling said switches to successively vary the field excitation of said generator and that of said motor.

7. In an electrical system, the combination with a generator having a field-magnet winding, and a resistor in circuit therewith, of means for controlling said resistor comprising a plurality of progressively actuated electromagnetic switches, and a relay having two opposing coils, one of which is connected across the terminals of said generator and the other of which is in circuit with the actuating coils of said switches.

8. In an electrical system, the combination with a generator having a field-magnet winding, and a resistor in circuit therewith, of means for controlling said resistor comprising a plurality of progressively actuated electromagnetic switches, a relay having two opposing coils, one of which is connected across the terminals of said generator and the other of which is in circuit with the actuating coils of said switches, and means for automatically controlling the number of actuating coils in circuit with said second relay coil so as to make the ampere turns of the two coils equal when the generator voltage reaches a predetermined value.

9. In a generator provided with a field-magnet winding and a resistor in circuit therewith, means for successively shunting portions of the resistor, and means for successively shunting substantially the whole resistor alternately with said first means.

10. In a control system, the combination with an electric generator having a field-magnet winding and a resistor in circuit therewith, of means for shunting increments of said resistor, and a relay for shunting portions of said resistor alternately with the shunting of successive increments.

11. In a control system, the combination with an electric generator having a field-magnet winding and a resistor in circuit therewith, of a controller, means operated by the controller for shunting successive incre-

ments of the resistor to increase the voltage of the generator, and means for temporarily shunting other portions of the resistor when the voltage of the generator is below that 5 which corresponds to the position of the controller.

12. In an electrical system, the combination with a generator having a field-magnet winding, and a resistor in circuit with said 10 winding, of means for successively shunting portions of the resistor to permit abnormal voltage values in said winding and means dependent upon the voltage of said generator for shunting other portions of the resistor, 15 to permit the current flow in said winding to become normal.

13. The combination with a dynamo-electric machine having a resistor, a switch for controlling a portion of said resistor and a 20 switch for controlling substantially the whole of said resistor, each having an actuating coil, of a relay for energizing the coil of said second-named switch and having opposing coils, one of which is responsive to 25 the electrical condition of said machine, and the other of which is responsive to the electrical condition of the coil of said first-named switch.

14. The combination with a dynamo-electric machine having a resistor, and means 30 for controlling successive increments of said resistor, of a pair of opposing forces for controlling substantially the whole of said resistor, one of said forces being responsive to 35 the electrical condition of said machine and the other of said forces being responsive to the electrical condition of said resistor.

15. The combination with a generator having a resistor, and means for short-circuiting 40 successive increments of said resistor, of a relay for short-circuiting substantially the whole of said resistor and having two opposing actuating coils, one of said coils being connected across the terminals of said generator and the other of said coils being controlled by said short-circuiting means.

16. The combination with an electric generator having a field-magnet winding and a resistor in circuit therewith, of an electric 50 motor, means for maintaining said resistor short-circuited during the acceleration of said motor, and means for inserting said resistor into circuit and short-circuiting said resistor in accordance with current conditions during the deceleration of said motor.

17. The combination with a pair of dynamo-electric machines, each having a resistor, of a switch for controlling each of said resistors and a switch for controlling the effect 60 of the operation of each of said switches.

18. The combination with a motor and a generator each having a field-magnet winding and a resistor in circuit therewith, of a fluttering relay for controlling each of said

resistors, and a switch for controlling the effect of the operation of each of said relays.

19. The combination with a pair of dynamo-electric machines, of three switches for controlling said machines, one of said switches, when it occupies one position, controlling one of said machines irrespective of the position of a second of said switches, and, when it occupies another position, controlling said one machine when said second switch occupies a predetermined position, 75 and said one switch controlling the other machine in accordance with the position of said third switch.

20. The combination with a dynamo-electric machine having a resistor and a reactive shunt, of a single-throw switch and a double-throw switch for controlling said resistor, each having a coil across the terminals of said reactive shunt, said double-throw switch having an additional 80 shunt coil and being adapted to control said resistor in one of its positions, irrespective of the position of said single-throw switch, and to control said resistor in its other position when said single-throw switch occupies 85 its closed position.

21. An electrical system comprising a dynamo electric machine, a resistor in the field-magnet circuit thereof, means for successively shunting increments of said resistor, 95 and means for temporarily shunting the remainder of said resistor alternately with the shunting of the increments.

22. An electrical system comprising a dynamo-electric machine, a resistor in the field-magnet circuit thereof, means for successively shunting increments of said resistor, and means for temporarily shunting supplementary and variable amounts of said resistor alternately with the shunting of the 105 increments.

23. In an electrical system, the combination with an electric generator having a field-magnet winding and a resistor in circuit therewith, of means for controlling the effective portion of said resistor, said means comprising a controller, a plurality of switches controlled by said controller, and a relay operable upon each actuation of said controller to a succeeding operative position 110 to shunt a portion of said resistor and to remove said shunt when the generator voltage reaches a value corresponding to the adjustment of the controller.

24. In an electrical system, the combination with an electric generator having a field-magnet winding and a resistor in circuit therewith, of means for controlling the effective portion of said resistor, said means comprising a manually operable controller, 120 a plurality of switches controlled by said controller, and means operable, when the voltage of the generator has a value below 125

- that for which the controller is adjusted, for shunting a portion of said resistor and for varying said shunted portion in accordance with the position of said controller.
- 5 25. In an electrical system, the combination with an electric generator having a field-magnet winding and a resistor in circuit therewith, of means for controlling the effective portion of said resistor, said means comprising a controller, means controlled by said controller for shunting a portion of said resistor, and means controlled in accordance with the value of the generator voltage relatively to that for which the controller is adjusted, for shunting a second portion of said resistor.
- 10 26. In an electrical system, the combination with an electric generator having a field-magnet winding and a resistor in circuit therewith, of means for controlling the effective portion of said resistor, said means comprising a controller, means controlled by said controller for shunting a portion of said resistor, and means controlled in accordance with the value of the generator voltage relatively to that for which the controller is adjusted, for shunting a second portion of said resistor and for varying said second portion.
- 15 27. In an electrical system, the combination with an electric generator having a field-magnet winding and a resistor in circuit therewith, of means for controlling the effective portion of said resistor, said means comprising a controller, means controlled by said controller for shunting a portion of said resistor and for varying said second portion.
- 20 28. In an electrical system, the combination with an electric generator having a field-magnet winding, of means for applying an abnormal voltage to said winding when the generator voltage is below its normal value, said means comprising a controller and means for varying the value of the voltage applied to said winding in excess of that for which the controller is adjusted in accordance with the position of said controller.
- 25 29. The combination with a motor and a generator having armatures connected in series and separately excited field-magnet windings, and an exciter having a field-magnet winding in series with said armatures, said motor having a field-magnet winding in series with the armature of said exciter, of resistors adapted to be inserted into circuit with said motor field-magnet windings, and means for simultaneously inserting portions of each of said resistors into circuit. 60 65
- In testimony whereof, I have hereunto subscribed my name this 11th day of May, 1916.
